CLAIM

The ornamental design for a massage oil bottle warmer, as shown and described.

DESCRIPTION

FIG. 1 is a front perspective view of a massage oil bottle warmer showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of a massage oil bottle placed on the warmer.

The broken lines in the drawings depict portions of the massage oil bottle warmer that form no part of the claimed design. The inner surfaces and structural portions of the recessed cylinder feature form no part of the claimed design.
